(57) **CLAIM**

The ornamental design for a bottle portion, as shown and described.

DESCRIPTION

FIG. 1 is a top, front, right side perspective view of our bottle portion;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings are included for the purpose of illustrating environmental structure and form no part of the claimed design.

The broken lines immediately adjacent to the shaded areas represent the boundaries of the claimed design, the broken lines forming no part of the claimed design.

1 Claim, 3 Drawing Sheets
